UNITED STATES PATENT OFFICE

2,443,176

V-OPENING SCREEN

Lloyd H. Banning, Trojan, S. Dak., assignor to
the United States of America as represented
by the Secretary of Interior

Application February 21, 1945, Serial No. 579,133

1 Claim. (Cl. 209—395)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

My invention relates to screen surfaces for the elimination of flat and elongated pieces from a mass of crushed rock. It is particularly adapted to provide a novel screen which is non-clogging and which may be substituted for a common form of screen, in a standard low head vibrating screen mechanism.

A preferred form of my invention is illustrated in the accompanying drawings in which:

Figure 1 is a plan view of my screen.

Figure 2 is a side elevation.

Figure 3 is an end elevation.

In these drawings:

A screen 21 includes a plurality of parallel screening bars 22, each having a downwardly and reversely-bent terminal portion 23. Alternating between but inclined to the bars 22 are a plurality of shorter bars 24 each having a down-turned portion 25.

One end of each bar 22 and 24 is rigidly secured in a transverse supporting member 26. The down-turned portions 23 and 25 are rigidly secured to a transverse support 27. The center lines of the bars 22 and 24 are in planes which intersect in the support 26 and diverge in the direction of the support 27. The bars 22 are also longer than the intermediate bars 24 for the purpose of eliminating a possibility of clogging my screen at the discharge side.

As the crushed rock is moved while being vibrated, by means not shown, from the left to the right of my screen, Figure 1, the flat and elongated pieces are progressively turned edgewise with their longest axis substantially parallel with my bars. These flat pieces fall through the V-shaped openings at points where a flat piece may pass edgewise through an opening. Obviously, my invention is also adapted for eliminating relatively flat pieces of slate from crushed anthracite coal.

The bars of my screen may be formed of tubing into which the end of a solid bar may be inserted, the two being rigidly connected either detachably to provide for renewing worn-out tubes, or permanently as by spot welding for simplicity and reduction of the first cost.

My invention may be applied to an inclined stationary screen by the addition of side mem-

2

bers parallel to the bars, and may also be applied to the cylindrical type by substituting for the supporting member 26 a circular member and for the member 27 a circular member larger than the first.

While I have shown and described certain embodiments of my invention, it is to be understood that it is capable of many modifications and changes in the construction and arrangement without departing from the spirit and scope of the invention, as disclosed in the appended claim, in which it is my intention to claim all novelty inherent in my invention as broadly as possible in view of the prior art.

15 15 What I claim is:

A screen of the class described comprising two spaced supports, a plurality of parallel bars each having one down-turned end terminally secured to said supports, a second plurality of parallel bars alternating with said first bars each bar being longer than said first set and having one down-turned end longer than those of said first set and being reversely bent and secured to said supports, whereby said second bars provide a supporting surface upwardly inclined with respect to said first set and form with said first set a plurality of V-shaped openings inclined to the general contour of the screen and both sets of bars are higher than the support at the discharge end of the screen.

LLOYD H. BANNING.
